UNITED STATES PATENT OFFICE.

EDWIN BOWEN HEAFORD, OF OMAHA, NEBRASKA.

TELEPHONE SYSTEM.

No. 858,454.

Specification of Letters Patent.

Patented July 2, 1907.

Application filed December 31, 1906. Serial No. 350,146.

To all whom it may concern:

Be it known that I, EDWIN BOWEN HEAFORD, a citizen of the United States, residing at Omaha, in the county of Douglas and State of Nebraska, have invented 5 a new and useful Telephone System, of which the following is a specification.

This invention relates to improvements in common battery telephone systems of the multiple type and it relates more particularly to improvements whereby a 10 cord circuit may be employed having only two wires, as distinguished from the usual three wire circuit and the accompanying complicated apparatus at the switch board.

The invention has for one of its objects to improve 15 and simplify switch board circuits of the character referred to, so as to be comparatively inexpensive and easy to construct, thoroughly reliable and efficient in service and designed to eliminate certain of the complications at the switch board.

20 A further object of the invention is the provision of a two wire cord circuit adapted to be used in connection with line circuits having improved line relays for the signal and improved arrangement of the cut-out relays.

With these objects in view, and others, as will appear as the nature of the invention is better understood, the invention comprises the various novel features of construction and arrangement of parts, which will be more fully described hereinafter and set forth with particularity in the claims appended hereto.

30 In the accompanying drawings, which illustrate certain of the embodiments of the invention, Figure 1 is a diagrammatic view of a portion of a telephone circuit showing the various apparatus in normal condition Fig. 2 is a similar view showing the system in condition for conversation between subscribers.

Corresponding parts in the several figures are indicated throughout by similar characters of reference.

In the present instance, I have elected to illustrate only those portions of the cord and switch board circuits which are necessary to an understanding of the invention, hence only one subscriber's line with its necessary apparatus at the switch board and only one-half of the cord circuit have been shown, the usual listening and ringing keys and cord plug at the opposite end of the cord circuit having been eliminated since these are of the usual character employed in standard multiple switch boards.

Referring to the drawings, A designates one of the subscriber's stations of the telephone system and B the central exchange, each having respectively a line circuit 1 and 2 and cord circuit 3 and 4. The apparatus at the subscriber's station may be of any approved house telephone susceptible to adaptation to the present invention. At the central station or exchange is the battery 5 to the terminals of which are connected, through the usual existing wires, the inner sleeve sides 3 and

4 of the cord circuit. The wires 3 and 4 have included therein the coils 7 and 8 of the differentially wound relay 9 at low resistance, and from the relay the two sides of the cord circuit lead to the plug 10 of the switch 60 board jack 11. Bridged across the exchange battery 5 is the operator's supervisory lamp 12 whose circuit 13 is connected in series with the armature 14 of the supervisory relay 9. Suitable non-inductive shunts 15, or equivalent means, are bridged across the coils 7 and 8 65 of the supervisory relay so as to prevent the choking effect of self induction of the relay coils during the passage of the talking current over the system. Connected between the two sides of the cord circuit between the exchange battery and other plug of the circuit, the usual listening and ringing keys are employed in the customary manner.

At the switch board end of the line circuit 1 and 2 is a line relay 16 of high resistance bridged across the wires 1 and 2 through the armatures 17 and 18 on opposite 75 sides of the cut-off relay, designated generally by 19, and, included in the wires 20 and 21 of the line relay circuit is the battery 22 having its negative terminal connected to ground at 23. The coil 24 of the line relay connected with the positive side of the signal line battery 22 is inductively wound on the core, while the coil 25 is non-inductively wound for the purpose of preventing fluttering of the line lamp 26 in case the cut-off relay 19 is somewhat slow in acting. The signal lamp 26 is connected across the battery 22 by the wires 27 85 and 28, the latter being in series with the armature 29 of the line relay. The coil 30 of the cut-off relay is of relatively low resistance and connected in series with the side 1 of the line circuit and spring 31 of the jack 11. The sleeve spring 32 and test thimble 33 of the jack are connected to ground through the wire 34, armature 35 of the cut-off relay, and resistance 36, said resistance being of sufficient value to keep down the current flow to the desired point for the battery voltage employed. Bridged across the springs of the jack is the comparatively high resistance and impedance coil 37 wound inductively on the coil of the cut-off relay and connected in series with the condenser 38. The coil 37 90 serves to actuate the relay 19 by the ringing current so as to prevent ringing through the line relay 16 and connect the sleeve spring of the jack with the wire 2 of the subscriber's line through the armature 35. Bridging the cut-off relay is a non-inductive shunt 39 of high resistance through which the ringing current passes from the wire 1 to the tip spring of the jack and thence to the grounded side of the cord circuit. The shunts of the differentially wound relay 9 and cut-off relay may, with advantage, be wound on the coils thereof so as to constitute a unitary piece of apparatus for convenience of installation. In practice, the resistance of the cut-off relay may be from thirty to forty-five ohms, and the shunt 39 thereof about half again as much. The coils

of the supervisory relay 9 may be of a resistance varying from eighteen to thirty ohms, while their shunts are about one half greater. The resistance of the line relay coils may be from one to two thousand ohms each.

5 When the subscriber A desires to communicate with another subscriber, he removes the receiver from the house telephone and the signal lamp 26 is thereby lighted, current flowing from the positive side of the line battery 22 through coil 24 of the line relay 16, 10 armature 17, wire 2, through the transmitter and receiver of the telephone, wire 1, armature 18, wire 21, coil 25, to ground 23. The coil 24 causes the armature 29 to close the signal lamp circuit so that current passes from the positive side of the battery 22 through 15 line 27, lamp 26, line 28, armature 29 to the grounded side of the battery. Upon seeing the signal, the operator inserts the answering plug 10 of the cord circuit into the jack 11 to ascertain the number of the subscriber to be called. The cut-off relay is actuated only 20 when the plug is inserted and the receiver is off the hook of the subscriber's telephone. Current continues to momentarily flow from the battery 22 through the wires 1 and 2, but, instead of passing to ground 22 through the armature 18, wire 21 and coil 25, the current passes through the coil 30 of the cut-off relay, jack spring 31, tip of the answering plug, wire 3 of the cord circuit, to the grounded side of the exchange battery 5. This energizes the cut-off relay 19 so that its three armatures are thereby actuated and assume the position 25 shown in Fig. 2. The signal lamp and line relay are thus cut out of the line circuit, and the cord and line circuits are connected together so that the exchange battery 5 supplies the talking current. After the exchange operator receives the number of the subscriber 30 to be called, she inserts the call plug into the proper jack so that the subscribers will be connected for conversation. As soon as the conversation is over, the subscriber A hangs up the receiver, the cut-off relay is de-energized, and current flows from the exchange battery 5 through the coil 8, side 4 of the cord circuit, plug and jack, and to ground through the wire 34, armature 35 and resistance 36, the said armature returning to its 35 normal position upon the cut-off relay being deenergized. The current passing through the coil 8 of the supervisory relay causes the armature 14 to be attracted so that the supervisory lamp circuit is completed and the lamp lighted to inform the operator that the subscribers have finished.

When it is desired to call the subscriber at station A, 50 the operator tests the circuit to see if the subscriber to be called is connected with any other subscriber in the exchange, this being done by touching the tip of the plug 10 to the test ring 33 in the usual manner. If the subscriber's line is not busy, the plug 10 is inserted in the jack 11 and a ringing current sent through the circuit. Sufficient current passes from the sleeve spring 32 to the tip spring 31, or, in other words, from the side 4 to the side 3 of the cord circuit, through the condenser 38 and inductive coil 37 on the cut-off relay, that the 55 armature 35 is actuated to be connected with the wire 2 of the line circuit, thereby forming a path for the

ringing current on one side of the line circuit. The path for the current on the other side of the line circuit is through the resistance coil 39 bridging the cut-off relay. Since current passes through both coils 7 and 65 8 of the supervisory relay, the supervisory lamp 12 is not lighted. When subscriber A answers by taking off his receiver from the hook, the full talking current will pass through the cut-off relay, so that immediately the line relay will be cut out of circuit and the armature 70 35 disconnected from ground.

From the foregoing description, taken in connection with the accompanying drawings, the advantages of the arrangement of the various apparatus and of the method of operation will be readily apparent to those skilled in the art to which the invention appertains. I have described the principle of operation of the invention, together with the apparatus which I now consider to be the best embodiment thereof, but I desire to have it understood that the apparatus shown is merely illustrative, and that various changes may be made, when desired, as are within the scope of the claims.

What is claimed is:-

1. In a telephone system, the combination with a central station, and a subscriber's station, of a cord circuit, a line circuit, a plug and jack for connecting the circuits, a signal controlling relay circuit bridging the line circuit, a cut-off relay for controlling the said relay circuit, and a resistance and impedance circuit bridging the springs of the jack and inductively related to the cut-off relay. 85

2. In a telephone system, the combination with a central station, and a subscriber's station, of a suitable cord circuit, a line circuit, a signal controlling relay connected across the line circuit, a cut-off relay in the line circuit for controlling the said relay, a resistance and impedance containing conductor bridging the line circuit and inductively related to the cut-off relay and actuating the latter, and a non-inductive resistance arranged in shunt relation with the cut-off relay. 95

3. In a telephone system, the combination of two wires of a subscriber's line, a line relay connected across the wires, a signal controlling circuit associated with the relay, a source of energy included in the said circuit, a cut-off relay having its coil included in one of the said line wires and provided with armatures for connecting the line relay with the line wires, a conductor connected across the line wires and wound inductively on the cut-off relay, and a high resistance shunt connected around the cut-off relay. 100

4. In a telephone system, the combination of two wires of a subscriber's line, a double wound relay of high resistance connected across the line wires, a battery connected with the line relay, a signal circuit connected with the battery and controlled by the line relay, a cut-off relay having its coil connected with one of the line wires, a jack having its tip spring connected with the line wire containing the cut-off relay and its sleeve spring connected with the other line wire, a resistance containing conductor connected with the sleeve spring and to ground and including an armature of the cut-off relay, a test thimble connected with the said grounded conductor, a resistance containing conductor bridged across the jack springs and inductively related to the cut-off relay, and a non-inductive resistance arranged in shunt relation to the cut-off relay. 110

In testimony that I claim the foregoing as my own, I have hereto affixed by signature in the presence of two witnesses.

EDWIN BOWEN HEAFORD.
